DESIGN FOR A SHOE

Nathan Kenneth Kean, New York, N. Y., assignor to C. & A. Lo Presti Inc., New York, N. Y., a corporation of New York

Application February 26, 1934, Serial No. 50,860

Term of patent 3½ years

To all whom it may concern:

Be it known that I, NATHAN KENNETH KEAN, a citizen of the United States, residing in New York, in the county of New York and State of New York, have invented a new, original, and ornamental Design for a Shoe, of which the following is a specification, reference being had to the accompanying drawing, forming part thereof.

I claim:

The ornamental design for a shoe, as shown.

N. KENNETH KEAN.
